ELECTRICAL SOUND TRANSMISSION SYSTEMS

Philip Barnet Vanderlyn, Ickenham, England, assignor to
Electric & Musical Industries Limited, Hayes, England,
a company of Great Britain

Application August 16, 1955, Serial No. 528,583

Claims priority, application Great Britain August 18, 1954

5 Claims. (Cl. 179—100.1)

This invention relates to electrical sound transmission systems wherein electrical signals representative of sounds received at a plurality of microphones and transmitted to a plurality of loudspeakers are so modified that the sounds heard from the loudspeakers will convey to a listener positional impressions of the sound sources, similar to those which would be produced naturally if the listener were present during the emission of the original sounds. Such a system is commonly referred to as a binaural system and it may include means for recording and reproducing the sounds and/or means for transmitting and receiving the sounds by wire or radio.

In one known type of binaural transmission system as described in U. S. patent specification No. 2,093,540 the apparent spatial distribution of the sound sources is derived on the assumption that a listener localises a source by means of phase differences existing at his ears at low frequencies, and by means of intensity differences at high frequencies. Low frequencies may be defined approximately as those frequencies for which the effective ear spacing is less than one half of the wavelength and high frequencies as those above this limit. The frequency at which the human brain changes over from phase discrimination to intensity discrimination has been stated to occur in the region of 700 cycles/sec. but depending on the circumstances and from person to person this changeover frequency may vary within wide limits.

As described in the aforementioned patent specification, phase differences at low frequencies can be produced at the listener's ears by the vector addition of the components at each ear due to each of two or more spaced loudspeakers, the phase differences being produced at the ears as a result of relative amplitude differences between the loudspeakers. At high frequencies intensity differences can also be produced at the ears as a result of relative amplitude differences between the loudspeakers.

It has been realised that for any given arrangement of two or more loudspeakers the relative amplitude differences required to reproduce the effect of sound arriving from a given angle will not be the same at both high and low frequencies, and it has been proposed to overcome this difficulty by employing a multiplicity of loudspeakers, and distributing the transmitted signals to the loudspeakers on an appropriate frequency selective basis so that the effective spacing of the loudspeakers is different at low and high frequencies.

The object of the present invention is to overcome the aforementioned difficulty without the use of a multiplicity of loudspeakers as heretofore and the frequency selective networks associated therewith.

A further object of the invention is to provide an improved binaural sound transmission system by means of which more accurate binaural effects can be produced.

In a two-channel binaural system of the type described in the aforementioned patent specification, the impulses from two microphones are modified to produce initial summation and difference signals by transmitting said impulses through so-called "summation" and "difference"

2

channels which are arranged so that the resulting current derived from the summation channel represents half the sum (that is, the mean) of the original microphone currents, while the current derived from the difference channel represents half the difference of the original microphone currents. Alternatively, the microphone system may be such that two outputs obtained therefrom are effectively equivalent to initial summation and difference signals. In either case it is known that if the initial summation and difference signals are modified so as to increase or decrease the amplitude of the difference signals as a whole relatively to the amplitude of the summation signals, and the modified signals are again summed and differenced, an angular magnification or reduction will be produced in terms of the original obliquity of the sound source with reference to the microphones. In other words, when sets of signals modified in the manner described are reproduced by spaced loudspeakers the listener will obtain the impression of the sounds arriving from a greater or smaller angle as the case may be, as compared with the original angle of the sounds relatively to the microphone system by which they were picked up.

According to the present invention there is provided a binaural sound transmission system comprising means for deriving two sets of signals with such relative amplitude differences that on applying said sets of signals to spaced sound reproducers a binaural effect is produced, and means whereby the relative amplitudes of the high and low frequency components of said sets of signals are modified thereby to produce a frequency sensitive angular magnification or reduction so as to reduce inaccuracies in said binaural effect.

In order that the invention may be clearly understood and readily carried into effect, an embodiment thereof will now be described, by way of example, with reference to the accompanying drawings, in which:

Figures 1 and 2 illustrate networks for insertion into the difference and summation channels, respectively, and

Figures 3 and 4 are explanatory diagrams.

Figure 3 illustrates diagrammatically a pair of spaced loudspeakers 1 and 2 arranged symmetrically with reference to a medial plane A—B. Let it be assumed that the loudspeakers are fed with two sets of signals derived from a binaural transmission system according to the aforementioned patent specification, said signals being in phase but differing in amplitude in order to convey to a listener at P positional impressions corresponding to an original sound source. Thus the listener at P will estimate the position of a virtual source at an angle θ to the medial plane A—B in accordance with the amplitude differences of the sounds reproduced by the loudspeakers 1 and 2.

If the sets of signals fed to the loudspeakers 1 and 2 are restricted firstly to the low frequency components below the aforementioned changeover frequency of about 700 cycles/sec. and then to the high frequency components above this frequency, the apparent angle θ of the virtual source for low and high frequency components respectively can be plotted against the amplitude ratio r of the reproduced sounds as shown by the curves of Figure 4, in which values of r and θ to suitable scales are represented along the axes XOX' and YOY' respectively. For the low frequency components the curve obtained approximates to the full-line AOA' passing through the origin O, but for the high frequency components the dotted line curve is obtained which intersects the low frequency curve at the origin O and at the points A and A' where the amplitude of the sounds produced by one of the loudspeakers is substantially zero. Thus, it will be appreciated that if the loudspeakers 1 and 2 reproduce signals derived from a virtual point source having

both high and low frequency components, the listener at P is liable to estimate the position of the virtual source at one angle in respect to the low frequency components and at a different angle in respect of the high frequency components. The present invention provides means whereby this inaccuracy in the binaural effect can be reduced or substantially eliminated so that the dotted-line curve of Figure 4 will be in closer conformity with the full-line curve.

According to one embodiment of the invention, as illustrated in Figure 1, the initial difference signals are fed through a channel including a bridged T-network which comprises a shunt arm including the series combination of resistor R_1 and capacitor C_1 , and series arms including the resistors R_2 and R_3 , the resistor R_1 of the shunt arm being connected to the junction of resistors R_2 and R_3 . The series arms are bridged by an inductance L_1 . This type of equaliser section attenuates the high frequencies relatively to the low frequencies but in addition it introduces an undesired phase shift in that portion of the frequency spectrum in which the reactances of L_1 and C_1 are comparable with the characteristic impedance of the circuit, and this phase shift produces undesired effects in subsequent summing and differencing operations. To correct this relative phase shift, a pair of all-pass bridged T-networks are connected, one in each channel, to introduce equal and opposite relative phase shifts in a known manner, the network L_3 , T_2 , C_3 being inserted in the difference channel as shown in Figure 1 and the network L_2 , T_1 , C_2 being inserted in the summation channel as shown in Figure 2.

It will be appreciated that the required frequency sensitive angular magnification or reduction could be attained as a result of the insertion of a suitable network in either the summation or the difference channel. However, if the initial summation signals are modified in a frequency sensitive manner an overall frequency discrimination is applied to the system. Some frequency discrimination will occur as a result of the modification of the initial difference signals but in general to a smaller extent.

As a result of the modification of the relative amplitudes of the high and low frequency components of the initial difference signals or summation signals as the case may be, it is possible to produce, by further summing and differencing operations, a frequency sensitive angular magnification or reduction. Thus, by suitably selecting the extent of the frequency sensitive modification of the difference or summation signals the disparity referred to in connection with Figures 3 and 4 can be largely overcome, and two sets of signals can be derived for energising spaced loudspeakers so as to convey to a listener the effect of both low and high frequency sounds arriving more nearly from the same angle.

In a two-channel binaural system according to the invention the two outputs from a particular type of microphone system may be effectively equivalent to initial summation and difference signals respectively, and in such a case the two outputs can be modified in the manner described before being subjected to summing and differencing operations to obtain the required frequency sensitive angular magnification or reduction. If, however, the microphone system is not of this type, preliminary summing and differencing operations are required to produce the initial sum and difference signals and the signals thus obtained are subjected to frequency sensitive modification according to the invention before being subjected to further summing and differencing operations so as to obtain the required two sets of signals.

A binaural system according to the invention is particularly applicable to arrangements in which only a single pair of loudspeakers is intended to be employed. The invention is, however, not to be considered as limited to the case in which only two loudspeakers are used since the invention, in general, allows the required number of loudspeakers to be reduced and in particular circumstances it may be desirable to utilize more than two loudspeakers whilst still obtaining the advantages of the present invention.

Binaural sound transmission systems of the type described are particularly suitable for use in the production of binaural sound records such as twin-track magnetic tapes carrying complementary signals along the respective tracks thereof. To produce such binaural sound records it is necessary to employ a sound recording system comprising a pair of discrete recording channels for recording the two sets of signals derived from the binaural transmission system. It will be appreciated that by employing a binaural transmission system according to the present invention to feed the two sets of signals to the discrete recording channels, the resulting sound records will be improved in that when reproduced by suitable apparatus they will convey to a listener more faithful positional impressions corresponding to the distribution of the original sound sources.

What I claim is:

1. In a binaural sound transmission system including means for deriving two sets of in-phase signals with such relative amplitude differences that on applying said sets of in-phase signals to spaced sound reproducers a binaural effect is produced, the provision of frequency selective means to effect modification of the relative amplitudes of the high and low frequency components of said sets of in-phase signals thereby to produce a frequency sensitive angular magnification or reduction so as to reduce inaccuracies in said binaural effect.

2. A binaural sound transmission system according to claim 1 including means for deriving initial summation and difference signals and means for summing and differencing said initial summation and difference signals thereby to obtain said two sets of in-phase signals, said frequency selective means effecting modification of said initial summation and/or difference signals.

3. A binaural sound transmission system according to claim 2 wherein said frequency selective means reduces the amplitude of the high frequency components of said initial difference signals as compared with the amplitude of the low frequency components thereof.

4. A binaural sound transmission system according to claim 3 wherein said frequency selective means comprises an attenuator in the form of a T-network having a shunt arm including resistance and capacitance and series arms each including resistance, said series arms being bridged by a path including inductance.

5. A binaural sound transmission system according to claim 4 including all-pass networks through which the modified initial difference signals and the initial summation signals are fed thereby to produce equal and opposite relative phase shifts to correct for any undesired phase shift introduced by said attenuator.
